Arthur P. Boller, Oak Park, Ill., assignor to S. C.
Lawlor Company, Chicago, Ill., a corporation
of Illinois

Application March 9, 1938, Serial No. 75,694

Term of patent 14 years

To all whom it may concern:

Be it known that I, Arthur P. Boller, a citizen of the United States, residing at Oak Park, in the county of Cook and State of Illinois, have invented a new, original, and ornamental Design for a Housing for Floor Treating Machine, of which the following is a specification, reference being had to the accompanying drawing, forming part thereof.

Fig. 1 is a perspective view of a housing em-

bodying the design as viewed from the front and left;

Fig. 2 is a perspective view of the housing as viewed from the side; and

Fig. 3 is a plan view of the housing.

I claim:

The ornamental design for a housing for floor treating machine, as shown.

ARTHUR P. BOLLER.
